(57) **CLAIM**

The ornamental design for a playing card shuffler and case as shown and described.

DESCRIPTION

FIG. 1 is a top front perspective view of the playing card shuffler and case according to my design;

FIG. 2 is a bottom perspective view of the playing card shuffler and case;

FIG. 3 is a top plan view of the playing card shuffler and case;

FIG. 4 is a cross-section view of the playing card shuffler and case;

FIG. 5 is a bottom plan view of the playing card shuffler and case;

FIG. 6 is a front elevation view of the playing card shuffler and case, the rear view being a mirror image thereof;

FIG. 7 is a right-side elevation view of the playing card shuffler and case; the left side being a mirror image thereof;

FIG. 8 is a top front perspective view of the playing card shuffler and case in an open configuration;

FIG. 9 is a top plan view of a second embodiment of the playing card shuffler and case; wherein the front, rear, top, bottom and side views are identical to the first embodiment;

FIG. 10 is a cross-section view of the playing card shuffler and case;

FIG. 11 is a top plan view of a third embodiment of the playing card shuffler and case; wherein the front, rear, top, bottom and side views are identical to the first embodiment;

FIG. 12 is a cross-section of the playing card shuffler and case;

FIG. 13 depicts the playing card shuffler and case in an environment of use; and,

FIG. 14 depicts the playing card shuffler and case in an open configuration in an environment of use.

The broken lines shown form no part of the claimed design.

1 Claim, 10 Drawing Sheets
